UNITED STATES PATENT OFFICE

127,816

DESIGN FOR A COMBINATION VANITY AND LIPSTICK CASE

Garland Dee Runnels, New York, N. Y.

Application January 3, 1941, Serial No. 97,791

Term of patent 14 years

To whom it may concern:

Be it known that I, Garland Dee Runnels, a citizen of the United States, residing at New York city, county and State of New York, have invented a new, original, and ornamental Design for a Combination Vanity and Lipstick Case, of which the following is a specification, reference being had to the accompanying drawing, forming part thereof, wherein:

Fig. 1 is a perspective view of a combination vanity and lipstick case in closed position, showing my new design;

Fig. 2 is a rear end view thereof;

Fig. 3 is a bottom plan view thereof;

Fig. 4 is a perspective view of the bottom section of the case shown in Figs. 1, 2 and 3 in open position; and

Fig. 5 is a similar view of the top section in open position, with the lipstick container withdrawn from its housing.

I claim:

The ornamental design for a combination vanity and lipstick case, substantially as shown.
